UNITED STATES PATENT OFFICE.

HERMAN TURTLETAUB, OF PERTH AMBOY, NEW JERSEY.

DESIGN FOR A GLASS BOTTLE.

Application filed April 15, 1925. Serial No. 13,138. Term of patent 7 years.

To all whom it may concern:

Be it known that I, HERMAN TURTLETAUB, a citizen of the United States, residing at Perth Amboy, in the county of Middlesex and State of New Jersey, have invented a new, original, and ornamental Design for Glass Bottles, of which the following is a specification, reference being had to the accompanying drawing, forming part thereof.

The figure is a side elevational view of a glass bottle, showing my new design.

I claim:

The ornamental design for a glass bottle, as shown.

HERMAN TURTLETAUB.
